UNITED STATES PATENT OFFICE.

WILLIAM L. AFFELDER, OF CRAFTON, PENNSYLVANIA.

PORTABLE CONTAINER.

1,414,392.

Specification of Letters Patent. Patented May 2, 1922.

Application filed November 1, 1919. Serial No. 335,101.

To all whom it may concern:

Be it known that I, WILLIAM L. AFFELDER, a citizen of the United States, residing at Crafton, in the county of Allegheny and State of Pennsylvania, have invented a new and useful Improvement in Portable Containers, of which the following is a full, clear, and exact description.

The present invention relates broadly to portable containers, and, more particularly, to metallic containers of this character adapted for comparatively rough usage.

The principal object of the present invention is to provide a portable container having a removable cover adapted to be secured in position by the carrying means for the container.

Another object of the invention is to provide means for carrying the container and securing the cover in position thereon, which means is so constructed as to prevent accidental disengagement thereof.

A further object of the present invention is to provide a carrying device for a container of the type described, so constructed that the entire bottom of the container receives and aids in the support of the load.

The foregoing and other objects, together with their attendant advantages, will be apparent as the invention becomes better understood by reference to the accompanying specification and drawings forming a part thereof, it being premised that changes may be made in the various details and the manner of operation within the scope of the appended claims without departing from the spirit of the invention.

Figure 1 is a top plan view of my improved container having the cover and carrying device in position.

Figure 2 is a longitudinal section on the line II—II of Figure 3, and

Figure 3 is a transverse section on the line III—III of Figure 2.

The present invention is intended particularly for use in mines, where it is desired to transport sets of bits or cutters between the mine and the shop as becomes necessary for sharpening and repairing purposes. For this purpose, the container is constructed of comparatively heavy metal to adapt the same for the rough usage which it must receive and is of such size that at least one set of bits or the like may be easily placed therein.

It is essential that containers of this char-

acter be provided with covers which may be easily secured in position to prevent loss of the contents of the container, and which covers cannot become accidentally disengaged during the carrying of the container from place to place.

As it is obvious that the invention is clearly adaptable for other purposes, I do not desire to limit myself to use in this connection, but have described this use as being one of the problems which the present invention solves.

Referring more particularly to the drawings, my container comprises a main body, which may be of any suitable construction, but made preferably of sheet metal folded to produce sides and ends 2 having an integral bottom 4. The overlapping portions of the metal at the ends of the container may be firmly secured in position by the use of suitable fastening means such as rivets 5.

In the preferred construction, the bottom 4 of the container is provided with an upwardly pressed portion 6 adapted to receive therebeneath the angular projection 7 formed on the lower end of the post 8. The portion 6 is preferably pressed upwardly a sufficient distance so that when the angular projection is secured beneath the same by means of rivets or the like 9, the entire bottom of the container will lie in substantially the same plane. Due to the particular mode of attachment of the lower end of the post, it will be apparent that the weight of the container and contents is distributed over the bottom of the container and is not taken entirely by the fastening devices 9, as would be the case if the angular projection 7 were secured interiorly of the bottom 4. This constitutes an important detail of the present invention, although this particular mode of attachment is not absolutely essential.

The L-shaped post 8 preferably projects substantially centrally through the body of the container above the top thereof and is provided with an opening 10 adapted to receive a carrying member which may be conveniently formed of a piece of wire or rod, bent upon itself to form a hook-shaped handle portion 11 and a restricted throat portion 11a. In addition to performing the function of a carrying handle for the container, this member 11 operates to hold the cover 12 in position on the top of the container. The cover 12 is preferably con-

structed with a central opening 14 of somewhat larger dimensions than the dimensions of the post 8 over which it is adapted to fit comparatively easily. The cover 12 may 5 also be provided with downwardly projecting flanges 15. These flanges 15 are also preferably formed on the cover in such manner that they play between the interior sides thereof and the exterior sides of the body 10 of the container is permitted. By making the dimensions of the cover slightly oversize, its ready application to the container is facilitated. As soon as the cover has been placed in position, the carrying member 11 may be passed through the opening 10 in the upper end of the post by so arranging the same that the restricted throat portion 11^a of the carrying member straddles the neck portion 17 of the post 20 formed by the depression 17 in the extreme upper end thereof. As will be noted from the drawings, this member normally tends to be in flatwise position on the cover; and as the thickness of the metal on the opposite 25 sides of the opening 10 in the post is preferably greater than the width of the restricted throat 11^a, accidental disengagement of the carrying member with the post is prevented. The carrying member not only 30 forms a handle by which the container may be carried in the hand, but also serves as means by which it may be hung on a mine car, or otherwise secured or suspended for transportation.

35 The advantages of the present invention reside in a construction in which the cover may be easily applied to the container and which, when once applied, is prevented from accidental removal by the insertion of the 40 combined carrying and locking member.

I claim:

1. In a portable container, a post secured to the bottom thereof and projecting upwardly therefrom above the top of the container, a cover having an opening adapted to 45 pass over said post, and a carrying member for said container cooperating with said post and preventing the removal of said cover, said carrying member having a restricted 50 throat portion preventing accidental disengagement thereof from said post, substantially as described.

2. A carrying device for portable containers, comprising a central post secured to the 55 bottom of the container and projecting upwardly therefrom above the top of the con-

tainer, and a carrying member cooperating with said post, said carrying member having a restricted throat portion preventing accidental disengagement thereof from said post, substantially as described. 60

3. A carrying device for portable containers, comprising a central post secured to the bottom of the container, said post having an opening formed therein eccentrically with respect to the contour of the post whereby different thicknesses of metal are provided adjacent said opening, and a carrying member 65 cooperating with said post, said carrying member having a restricted portion permitting application only when in predetermined position, substantially as described. 70

4. A carrying device for portable containers, comprising a post secured to the bottom of the container and projecting upwardly 75 therefrom above the top of the container, and a carrying member cooperating with said post, said carrying member having a restricted throat portion preventing accidental disengagement thereof from said post, and said post having means whereby application of said carrying member when in predetermined position is facilitated, substantially as described. 80

5. In a portable container, a post secured 85 to the bottom thereof and projecting upwardly therefrom above the top of the container, a cover having an opening adapted to pass over said post, a carrying member for said container cooperating with said post and preventing accidental removal of 90 said cover, said post having a depression formed therein permitting the application and removal of said carrying member only when in alignment with said depression, 95 substantially as described.

6. A carrying device for portable containers, comprising a central post secured to the bottom of the container and projecting upwardly therefrom above the top of the container with an opening in said upwardly projecting portion above the top of the container, and a carrying member cooperating with said post, said post being shaped to present different thicknesses of metal at different portions around said opening permitting the carrying member to be applied when in a predetermined position only, substantially as described. 100 105

In testimony whereof I have hereunto set 110 my hand.

WILLIAM L. AFFELDER.
